(57) CLAIM

The ornamental design for a point of sale device, as shown.

DESCRIPTION

FIG. 1 is a front, right side, top perspective view of a point of sale device showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, left side, top perspective view thereof.

The broken line showing is for illustrative purposes only and forms no part of the claimed design.
